UNITED STATES PATENT OFFICE.

JAMES PHILLIP NOLAN, OF WESTFIELD, CONNECTICUT.

DESIGN FOR A GAME-BOARD.

SPECIFICATION forming part of Design No. 29,496, dated October 18, 1898.

Application filed September 16, 1898. Serial No. 691,116. Term of patent 8½ years.

To all whom it may concern:

Be it known that I, JAMES PHILLIP NOLAN, a citizen of the United States, residing at Westfield, in the county of Middlesex and State of Connecticut, have invented and produced a new and original Design for a Game-Board, of which the following is a specification, reference being had to the accompanying drawings, forming a part thereof.

Figure 1 is a plan view of a game-board embodying my design, and Fig. 2 is a section on the line 2 2 of Fig. 1.

The leading feature of my design comprises

a star-shaped figure 1, arranged within a rectangular base 2, the edges of said base being 15 raised. Following the outline of the star and slightly within its border is a rib 3, and arranged within the body of the star is a five-sided figure 4.

I claim—

The design for a game-board, herein shown and described.

JAMES PHILLIP NOLAN.
